WILLIAM F. SEMPLE AND R. W. STEPHENS, OF MOUNT VERNON,
OHIO.

Letters Patent No. 88,086, dated March 23, 1869.

IMPROVED MODE OF POLISHING HARD-RUBBER AND OTHER ARTICLES.

The Schedule referred to in these Letters Patent and making part of the same.

To all whom it may concern:

Be it known that we, WILLIAM F. SEMPLE and R. W. STEPHENS, of Mount Vernon, county of Knox, and State of Ohio, have invented a new and useful Improvement in the Manufacture of Hard Rubber, especially in the manufacture of rubber plates for dentists' use; and hereby declare the following a full, clear, and exact description thereof, reference being had to the accompanying drawing, and to the letters of reference marked thereon.

The nature of our invention consists in combining the principle of the usual polishing-wheel and polishing-belt, thereby obtaining the increased surface of the belt, with the solid contact and small curvature of the wheel.

The drawing is a representation in perspective of a machine, showing the embodiment of the principle of our invention, in which—

A is the polishing-belt;

B, the small wheel; and

d, the article to be polished, in the manner hereinbelow more fully set forth.

It is true, that for purposes of polishing spokes, augers, or other articles, polishing-belts, passing over two or more wheels, or rollers, are in common use, and serve only in securing an elastic contact between the belt and article to be polished.

We are also aware, that for polishing plates for artificial teeth, the best device now in use is the employment of a small wheel, varying in size from one-half inch to two and a half inches in diameter, and made of heavy leather; but the great difficulty in this case, (and which we avoid,) is, that the friction-surface, being so small, soon itself becomes polished, and its effectiveness is thus destroyed.

Our improvement consists in having the belt A run between the small wheel B and the article d to be polished, thus securing all the advantage of the smallest wheel, in getting into the inequalities of the article to be polished, and, at the same time, have as much friction-surface as we desire—more than could possibly be obtained from the largest-sized wheel, as the belt may be of any desired length.

Having thus fully described our invention, What we claim as new, and desire to secure by Letters Patent of the United States, is—

The combination of the wheel and belt, so as to operate substantially as described.

W. F. SEMPLE.

R. W. STEPHENS.
